UNITED STATES PATENT OFFICE.

ANTHONY LUCY, OF SAN FRANCISCO, CALIFORNIA.

DESIGN FOR CAKE OR BAR SOAP.

SPECIFICATION forming part of Design No. 14,444, dated November 27, 1883.

Application filed March 24, 1883. Term of patent 7 years.

To all whom it may concern:

Be it known that I, ANTHONY LUCY, a citizen of the United States, residing in the city and county of San Francisco, State of California, have invented and produced a new and original Design for Cake or Bar Soap, of which the following is a specification.

The nature and essential features of my said design are fully represented in the accompanying drawing.

My said design consists of a novel shape, form, or configuration produced by joining together two heart-shape outlines, A A, by their obtuse ends or points, so that they lie in the same plane and their indented ends b b point in opposite directions. The body of this figure is thin, somewhat like an hour-glass in shape, being smallest at the waist or center and greatest at the ends. The top and bottom

faces are flat, and a raised edge or marginal border is formed by sinking panels e e in the top and bottom faces. These panels serve to receive raised letters or ornamental figures, if desired, by which to mark the soap. The vertical edges or rim of this double or twin heart-shape figure are flat, or may be rounded, and the corners or angles may be removed by rounding or by beveling them to produce angular surfaces all round the edges.

Having thus fully described my invention, what I claim, and desire to secure by Letters Patent, is—

The design for cake or bar soap herein described and shown.

ANTHONY LUCY.
